United States Patent

Des. 235,491
Patented June 24, 1975

235,491

ELECTRIC TOOTHBRUSH

Norman Spiegel, New York, N.Y., assignor to Nasta
Industries, Inc., New York, N.Y.

Filed Oct. 17, 1973, Ser. No. 407,060

Term of patent 14 years

Int. Cl. D4—02

U.S. Cl. D4—15

FIG. 1 is a perspective view of an electric toothbrush, showing my new design;

FIG. 2 is a left side view thereof;

FIG. 3 is a left end view thereof;

FIG. 4 is a right end view thereof; and

FIG. 5 is a bottom view thereof.

I claim:

The ornamental design for an electric toothbrush, as shown.
